UNITED STATES PATENT OFFICE.

BENJAMIN CHAFETZ, OF NEW YORK, N. Y.

DESIGN FOR A MEDALLION OR SIMILAR ARTICLE.

Application filed May 26, 1925. Serial No. 13,567. Term of patent 3½ years.

To all whom it may concern:

Be it known that BENJAMIN CHAFETZ, a citizen of the United States, and resident of the city of New York, in the county of Bronx and State of New York, has invented a new, original, and ornamental Design for Medallion or Similar Article, of which the following is a specification, reference being had to the accompanying drawing, forming part thereof, in which—

Fig. 1 is a plan view of a medallion embodying my invention, and

Fig. 2 is a front elevational view thereof.
I claim:

The ornamental design for a medallion or similar article as shown.

Dated New York city, May 22, 1925.

BENJAMIN CHAFETZ.
